UNITED STATES PATENT OFFICE.

STEPHEN W. HEMSTREET, OF AUDUBON, IOWA.

BROOM-HOLDER.

1,105,428.

Specification of Letters Patent. Patented July 28, 1914.

Application filed February 10, 1914. Serial No. 817,840.

To all whom it may concern:

Be it known that I, STEPHEN W. HEMSTREET, a citizen of the United States, residing at Audubon, in the county of Audubon 5 and State of Iowa, have invented a new and useful Broom-Holder, of which the following is a specification.

The present invention appertains to broom holders, and aims to provide a novel and 10 improved device of that character.

It is the object of the present invention to provide a holder of the nature indicated, which shall be of such unique construction, and which shall be so operable, as to be 15 capable or receiving and gripping the handle of a broom, or the like, to support the same in a reliable and efficient manner, and to permit the handle to be readily withdrawn.

20 Another object of the present invention is to provide a holder which may be readily manufactured or fashioned from wire stock, and which will be simple, neat and inexpensive in construction, as well as being simple, 25 convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

The invention has been illustrated in its preferred embodiment in the accompanying drawing, wherein:

40 Figure 1 is a plan view of the improved holder. Fig. 2 is a front view thereof, a portion of the back or body being broken away.

In carrying out the present invention, there is provided a back or body 1, preferably, 45 although not necessarily, constructed of hard wood, and which is adapted to be secured to a wall or other supporting structure, by means of screws or other securing members. Carried by the back 1 is a stationary gripping member, projecting away 50 from the back, and a pivoted spring pressed gripping member coöperating with the stationary gripping member, as will be described more in detail presently.

55 The stationary gripping member 2 is bent from a length of wire or other suitable stock,

the wire being doubled with its sections or arms spaced apart and parallel. The terminals of the stationary gripping member 2 are engaged into or through the back 1, 60 whereby the said gripping member extends perpendicular or at right angles to the back, with the sections or limbs of the gripping member spaced vertically. The intermediate or central portions of the sections or arms 65 of the stationary gripping member are curved or bowed to form the arcuate jaw portions 3, and the bend or free portion of the gripping member 2 is bent angularly, to form an angular lip 4. The wire or stock 70 from which the stationary gripping member is formed, is relatively rigid, although it has sufficient resiliency for the purposes, the curved or arcuate portions 3 coöperating to provide a stationary, and slightly yield- 75 able, jaw. The pivoted gripping member 5 is also bent from a length of wire or other stock, the wire being doubled, and the end portions 6 of the sections or limbs being bent angularly from the central or inter- 80 mediate portions thereof. The central or intermediate portions of the sections or limbs of the pivoted member 5, are curved or bowed to form the arcuate or jaw portions 7 normally projecting away from the 85 back and coöperating with or complementing the jaw portions 3 of the stationary gripping member, while the bend or free portion of the pivoted gripping member 5 is bent angularly, to provide an angular lip 8 90 coöperating with the lip 4 of the stationary gripping member. The sections or arms of the pivoted gripping member are spaced apart vertically, the terminal of the upper section or arm being formed into an eye 9, 95 and the lower terminal portion 6 having an upturned spindle 10 having its free or upper end engaged through the eye 9.

The spindle 10 is pivoted to the back 1 remote from the stationary gripping mem- 100 ber, by means of a pair of staples or bearing members 11 engaged to or through the back 1, the staples or bearings 11 being disposed adjoining the respective terminal portions 6. The spindle or pivoted portion 10 of the 105 pivoted gripping member is disposed adjoining one side edge of the back 1, while the stationary gripping member is disposed adjoining the other side edge of the back, it being noted that the portions 6 of the piv- 110 eted gripping member normally extend along the back and are turned away from the

basal portion or butt end of the stationary gripping member, and that the jaw of the pivoted gripping member formed by the curved portions 7, normally coöperates with 5 the jaw of the stationary gripping member. The angular lips 4 and 8 of the stationary and pivoted gripping members, respectively, form a tapered mouth or entrance to the space between the jaws, there being a constricted throat between the lips and jaws, as 10 is clearly apparent by reference to the drawing.

In order to spring press the pivoted gripping member to normal or active position, a 15 coiled wire torsional spring 12 is disposed on the spindle 10 of the pivoted gripping member, and has one terminal portion 13 formed with a hook 14 engaging over one of the portions 6 of the said gripping member, while the other terminal portion 15 of the spring bears against the back 1, to 20 press the pivoted gripping member toward the back 1 and the stationary gripping member.

25 In use, the back 1 may be readily secured to the wall or other supporting structure, upon which it is desired to support the broom, the jaws or gripping members being arranged horizontally with respect to 30 one another, whereby the broom handle may be supported in an upright or natural position. To insert the broom handle into the holder, the same need only be forced between the lips 4 and 8 of the gripping 35 members, which will cause the pivoted gripping member to swing away from the stationary gripping member, as indicated in the dotted line position of the gripping member 5 in Fig. 1, in order that the handle 40 may engage the jaw of the pivoted gripping member, in which event the pivoted gripping member will swing back toward the back or block 1, and the jaw of the stationary gripping member, the pivoted gripping 45 member being pressed inwardly toward the back 1 and stationary gripping member, under the influence of the spring 12, so that when the handle of the broom is released, the same will be snugly held between the 50 jaws. It is preferable to engage that portion of the broom handle which is of the smallest diameter, between the gripping members, in order to insure the proper suspension of the broom from the holder, although under 55 ordinary conditions, the tension of the spring 12 will be sufficient to grip the broom handle properly between the jaws. To release or withdraw the broom handle, it is merely necessary to pull or move the same 60 away from the back or block 1 of the holder, in which event the pivoted gripping member

will swing forwardly or outwardly, to permit the handle to disengage the jaws and move outwardly between the lips 4 and 8. One of the gripping members being stationary, and the other being pivoted, will enable the broom handle to be readily and effectively applied to and removed from the holder, particular attention being directed to the fact that the pivoted or movable 65 gripping member embodies the portions 6 which are pivoted to the back or block 1, to normally swing toward the back, and the jaw portions 7 which are disposed angularly with respect to the portions 6, whereby the 70 pivoted gripping member will open and close in a peculiar manner with respect to the stationary gripping member.

From the foregoing, taken in connection with the drawing, the several advantages 80 and capabilities of the present device will be obvious without further comment, it being noted that the objects aimed at have been carried out satisfactorily.

Having thus described the invention, what 85 is claimed as new is:—

A holder embodying a back, a stationary gripping member embodying a doubled wire having its terminals engaged to the back, having the intermediate portions of 90 its arms curved to provide a jaw, and having its free portion bent angularly to form a lip, a pivoted gripping member embodying a doubled wire having its terminal portions bent angularly, having its intermediate 95 portions curved to form a jaw coöperating with the aforesaid jaw, and having its bent portion bent to form a lip coöperating with the aforesaid lip, one terminal portion of the pivoted gripping member being 100 formed with an eye, and the other terminal portion having a spindle engaging through the said eye, bearings embracing the said spindle and engaged to the back, the terminal portions of the pivoted gripping member 105 normally projecting toward the terminal portions of the stationary gripping member, and a spring disposed upon the said spindle and having its terminal portions engaging the back and one of the terminals of the pivoted gripping member, to normally swing the said gripping member toward the back and stationary gripping member.

In testimony that I claim the foregoing 115 as my own, I have hereto affixed my signature in the presence of two witnesses.

STEPHEN W. HEMSTREET.
